DESIGN FOR A PADLOCK

David Papkin, New Haven, Conn., assignor to Sargent & Company, New Haven, Conn., a corporation of Connecticut

Application August 19, 1943, Serial No. 110,958

Term of patent 3½ years

To all whom it may concern:

Be it known that I, David Papkin, a citizen of the United States, residing in the city of New Haven, in the county of New Haven, State of Connecticut, have invented a new, original, and ornamental Design for a Padlock, of which the following is a specification, reference being had to the accompanying drawing forming part thereof, in which

Fig. 1 is a front elevational view of a padlock showing my new design;

Fig. 2 is a top plan view of the same; and
Fig. 3 is a side elevational view of the padlock.

I claim:

The ornamental design for a padlock, substantially as shown.

DAVID PAPKIN.
